2 SHEETS—SHEET 2.

UNITED STATES PATENT OFFICE

PHILIP HAAS, OF DAYTON, OHIO.

WATER-CLOSET VALVE.

1,111,747.

Specification of Letters Patent. Patented Sept. 29, 1914.

Application filed October 30, 1913. Serial No. 798,299.

To all whom it may concern:

Be it known that I, PHILIP HAAS, a citizen of the United States, residing at Dayton, in the county of Montgomery and State of Ohio, have invented new and useful Improvements in Water-Closet Valves; and I do hereby declare the following to be a full, clear, and exact description of the invention, such as will enable others skilled in the art to which it appertains to make and use the same.

My invention consists in the novel features hereinafter described reference being had to the accompanying drawing which illustrates one embodiment of my invention selected by me for the purpose of illustrating the same, and a slight modification thereof, and said invention is fully disclosed in the following description and claims.

20 My present invention relates particularly to that class of flushing apparatus which is used most largely where the water supply is comparatively small so that the water supply pipe with which the apparatus is connected does not furnish the water in sufficient quantity to enable it to be used directly from the supply pipe for flushing purposes, and in this class of devices it is customary to employ a flushing tank which is supplied with water from the water supply pipe, or main and when the flushing action takes place, the flushing is accomplished by means of the water discharged from said tank.

35 My invention provides for controlling and operating the valve mechanism of the apparatus by means of the pivoted closet seat and includes among its novel features, means whereby a very light spring may be employed 40 for normally holding the water inlet valve upon its seat, thus permitting the valve to be raised by a comparatively small amount of force exerted upon the valve stem in opposition to said spring, thus relieving the spud which connects the valve mechanism with the porcelain bowl, or other connecting means from transverse stress, which tends to injure the same or break the porcelain away where a very heavy spring is employed.

50 My invention also contemplates a novel valve construction for substantially balancing the water pressure and facilitating the movement of the valve in either direction and more specifically and in its preferred form,

my invention also contemplates the provision of connections independent of the main flushing connection for supplying water to the "jet" and also preferably to the rim of the bowl while the seat is in its lowest position so as to moisten the walls of the bowl, break the water seal of the bowl, and discharge an injector like stream from the jet through the empty trap and soil pipe so as to create a strong suction therethrough, which will effectually withdraw air continuously from the bowl and thoroughly ventilate the same during the use of the apparatus and while the seat is depressed. The importance of this ventilating feature can hardly be over-estimated. By its use an apparatus of this character can be installed in lavatories, in hospitals, and other places without the slightest possibility of contaminating the atmosphere of the room in which it is installed so that the closet becomes as innocuous as any ordinary piece of furniture. It may thus be installed, for example, in the bedroom of a hospital or of an invalid in a private house or in many other locations where the ordinary toilet apparatus would be extremely objectionable and unsanitary, without any inconvenience and without impairing the purity of the atmosphere of the room.

55 In a former application for Letters Patent of the United States filed by me on or about July 19, 1912, I have disclosed the broad idea of ventilating structure in connection with a specific form of valve mechanism, especially adapted for use where practically unlimited volume of water supply is available, such as in large office buildings and other buildings where a sufficient supply of water to effect the flushing without the use of an intermediate tank can be had, and my present invention is particularly designed to extend the advantages of this invention to that type of apparatus intended for use where a comparatively small supply of water is obtainable and the intervention of a supply tank is necessary.

60 It will also be understood that this apparatus can be utilized for positively ventilating the room in which it is installed, for if the inlet valve is open, as by depressing the closet seat by means of the hand or otherwise without any use of the closet, the water seal will be broken, as before described, the suction jet will be discharged through the

85

90

95

100

105

110

emptying trap and will operate continuously so long as the valve is held open, thus positively withdrawing large volumes of air from the room and discharging them through the soil pipe. The operation of the device may be continued for a sufficient period to thoroughly ventilate the room, such as a hospital room or the room of an invalid in a private home, or any other room or apartment in which the apparatus is installed. Obviously the air withdrawn from the room by the suction of the ventilating jet will necessarily be replaced by fresh air entering through the doors, windows, or otherwise from outside the room. It will thus be seen that this ventilating feature of my invention not only prevents the contamination of the air by the use of the apparatus in the ordinary manner, but may be employed independently as an active ventilating apparatus for changing the atmosphere of the room, if desired.

Referring to the accompanying drawing, Figure 1 represents a sectional view of a closet bowl provided with my improved flushing and ventilating apparatus. Fig. 2 is an enlarged sectional view of the valve casing, valve and connections. Fig. 3 is a view similar to Fig. 2 showing the valve body in raised or open position. Fig. 4 represents a sectional view through the valve and casing on the line 4—4 of Fig. 2 looking in the direction of the arrows. Fig. 5 is a sectional view of a modified form of valve and casing in which the ventilating feature hereinbefore referred to is omitted but the other advantageous features of the construction are retained.

Referring to the drawings, 1 represents the bowl provided with the bowl rim flush passage 2, trap 3, and discharge 4 connecting with the soil pipe.

5 indicates an aperture provided in the bowl structure for the insertion of a jet pipe 45 at the lower end of the trap portion communicating with the bowl proper and the bowl is also provided with an inlet aperture 6 connecting with the rim aperture 2 to receive the spud or main flush pipe connection, a second spud receiving aperture 7 connecting with the rim aperture 2, and an inlet aperture 8 at the lower part of the bowl for receiving the spud through which the jet pipe connection is made.

55 10 represents the valve casing which is open at the top and bottom and is provided on opposite sides with apertures substantially in line with each other. The bottom aperture is preferably the inlet aperture, although it is obvious that the valve mechanism could be turned upside down without departing from the spirit of my invention. The bottom portion of the valve casing is in this instance exteriorly screw threaded 65 to receive a clamping nut 11 provided at its

lower end with an annular nut which engages an annular shoulder of a collar 11* which is preferably exteriorly screw threaded to connect it with the water inlet pipe and the upper end of said collar is provided with a reduced aperture 12 and with an annular valve, the seat 13 surrounding said reduced aperture. The interior of the valve chamber is provided with a cylindrical portion 14 which forms a guide for the cylindrical valve body hereinafter referred to, the said cylindrical portion being provided with an aperture 15 communicating with the aperture 16 on one side of the valve casing which is connected with the main flushing aperture 6 as hereinafter described. The aperture 16 is shown in this instance as internally screw threaded. The valve casing 10 is provided as before stated with an aperture on the opposite side of the casing, here indicated at 17, which is also shown internally threaded, and the cylindrical portion 14 extends upward into that portion of the valve body opposite the lower portions of the apertures 15 and 16. A web 18 extends from the upper part of the valve body to the upper part of the cylindrical guiding portion across the upper portion of the aperture 16 so that the communication between the aperture 17 and the aperture 16, through the valve casing, must be through the upper part of said cylindrical guiding portion and through the lateral aperture 15 therein, as clearly shown in Fig. 2.

A hollow cylindrical valve body 20 is mounted in the cylindrical portion 14 so as to be capable of sliding easily, vertically therein, said body being closed at its lower end and provided with a valve 21 on its lower face, the said valve being preferably composed of rubber, fiber or other suitable material held in a recess formed in the bottom portion of reduced diameter with which the bottom of the valve body is preferably provided, said valve coacting with the valve seat 13 before referred to so as to open and close the water inlet aperture 12. A portion of the valve casing indicated at 22 below the cylindrical guiding portion 14 is of slightly larger diameter than the valve body as shown and the valve body is provided near the lower end of its hollow cylindrical portion with apertures 23 in its walls, the combined areas of said apertures being preferably somewhat less than the area of the aperture 12 in the preferred form of my invention, so that a portion only of the water admitted through the aperture 12 will pass through said apertures 23 into the interior of the valve body and upward there-through, when the valve is in raised position as hereinafter described. The valve body is provided with a vertically disposed stem 30 secured to the bottom thereof and extending upward out of the valve casing through the

80

75

100

105

110

115

120

125

130

top aperture therein, the said aperture being fitted with a closing cap or plug 24, which is preferably internally recessed on its lower face and provided with a packing washer 25 and metal washer 26 for compressing the packing and forming a stuffing box to prevent leakage around the valve stem.

27 represents a coil spring which preferably surrounds the valve stem, the lower end engaging the bottom of the interior of the cylindrical valve body, and the upper end engaging the washer 26, thus compressing the spring and also compressing the packing 25 between the washer 26 and the upper end of the recess in the plug or cap 24.

The diameter of the water inlet aperture 12 being small, a comparatively light spring can be used to hold the valve 21 seated on the valve seat 13 against the initial pressure of the water. It will also be noted that the interior diameter of the hollow valve body 20 is considerably greater than the diameter of said inlet aperture 12 so that when the valve body is in open position the water will exert some downward pressure on the interior bottom face of the valve body thus tending to balance the valve and facilitating the closing movement of the same against the water pressure.

The upper end of the valve stem 30 is preferably screw threaded and provided with an adjustable nut or equivalent device which engages a slot or recessed portion in a lever 31 secured to the hinged seat 32 in such a manner that when the valve is in its closed position the seat will be slightly raised from the top of the bowl at its forward edge, as shown in Fig. 1 so that the depression of the seat will compress the light spring 27 and raise the valve, thus opening the water supply inlet 12, the valve and the seat 32 being both restored to normal position by the spring 27. The lower part of the valve casting is preferably provided with a hollow extension 35 having therein a passage 36 communicating with the enlarged portion 22 of the valve casing surrounding the cylindrical valve body 20 and the extension 35 is preferably provided with two outlet apertures 37 and 38. The outlet aperture 38 is connected by means of a pipe 39 which extends through a spud and stuffing box of the usual construction indicated at 40, in the inlet aperture 8 of the bowl, the said pipe 39 being extended (preferably, but not necessarily) continuously, so that the discharge end of the pipe 39 extends through the jet receiving aperture 5 of the bowl, the discharge end of the pipe or jet being indicated at 41 and being arranged to discharge longitudinally of the adjacent portion of the trap 3 below the level of the liquid seal. The aperture 37 in the extension 35 of the valve casing is preferably connected by means of a

pipe 42 with a suitable spud or connection 43 so that it discharges through the aperture 7 which may be located at one side of the aperture 6 and which communicates with the rim flush passage 2.

The valve casing is connected by means of a spud 45 screw collar 46 and nipple 47 with the main flushing aperture 16 of the valve casing, so as to both connect the valve casing to the rim flush passage 2 and support the valve casing with respect to the bowl. The aperture 17 of the valve casing is connected by a pipe 50 with a tank 51, ordinarily a closed tank, which is located at a considerable distance above the level of the valve to give the required "head" or pressure to the water to effect a thorough flushing of the bowl after use in the manner hereinafter described, said tank being of suitable size for this purpose.

I will now describe the operation of my improved apparatus assuming the parts to be in a normal position with the seat slightly raised and the valve closed, as shown in Figs. 1 and 2. When the seat is occupied the forward edge will be depressed thereby raising the lever 31 and lifting the valve stem and valve against the pressure of the spring. Water supplied by the water inlet pipe will pass upwardly through the inlet aperture 12 around the cylindrical body of the valve and a portion only of the water will pass through the aperture or apertures 23 in the cylindrical valve body and thence upwardly through the valve body to the upper part of the valve casing. The valve body when in its lowest position is below the flushing aperture 15 but when the valve is raised the cylindrical body thereof closes said aperture as shown in Fig. 3. The incoming water which passes up through the hollow valve body therefor is delivered through the aperture 17 to the pipe 50 and thence to the tank 51 in which it accumulates during the time that the seat is occupied. The remaining portion of the water admitted through the inlet aperture 12 passes through the passage 36 in the extension 35 and thence a portion of the same passes through the pipe 42 to the rim flush discharging a quantity of water therethrough which wets the interior surfaces of the walls of the bowl above the liquid level of the water seal, which are normally dry, and thus tends to prevent the adhesion of any matter thereto. A portion of the water is also discharged downwardly through the pipe 39 to the jet from which it is discharged through a reduced aperture with great force. The action of this jet is two-fold. First, it starts the siphonic action of the trap and discharges the water in the trap portion of the bowl, thus breaking the liquid seal and establishing a free connection with the soil pipe. Second, it dis-

charges a strong injector spray or jet longitudinally through the adjacent portion of the trap and thence to the soil pipe which creates a strong suction through the trap, thus continually withdrawing large volumes of air from the bowl and also discharging the comparatively small quantity of water passing to the rim aperture through pipe 42 by reason of the velocity of the jet. The effect of the jet therefore is to maintain a free passage at all times when the seat is occupied between the interior of the bowl and the soil pipe and to positively withdraw not only the foul air therein, but to draw in volumes of air from the surrounding atmosphere of the room in which the bowl is located and positively prevent any foul air passing from the bowl to the room. As a result of this operation of the jet, the atmosphere of the room can not possibly be contaminated, and as before stated, the closet becomes entirely innocuous and may be employed in any location without danger of setting up unpleasant or unsanitary conditions. As soon as the seat is relieved, the spring 27 causes the front edge thereof to rise and simultaneously reseats the valve 21 on its seat 13 and closes the water supply, thus cutting off the supply of water to the pipes 39 and 42 and simultaneously opening the aperture 15 which is the main flushing aperture, thus permitting the water accumulated in the tank 51 to pass with great force and volume to the rim flush, this removing any contents of the bowl which may remain, thoroughly cleansing the bowl, and trap, and as the pressure and volume of the water subsides with the gradual emptying of the tank, the last portions of the water so admitted fills up the lower portions of the trap and restores the water seal, thus preventing any foul air or gas from passing from the soil pipe backwardly to the bowl.

In Fig. 5 I have illustrated a modification of my invention in which the valve casing is constructed exactly in the manner shown in Figs. 1 to 4 inclusive, except that the extension 35 and the pipe connections therefrom are omitted, and therefore the ventilating feature before referred to is not present in this modified form of the valve. This modification of the valve further retains the other features hereinbefore described. The parts of the valve shown in Fig. 5 are lettered to correspond with the similar parts shown in the other figures, the letter "a" following each reference numeral. In the operation of this form of the valve, when the seat is depressed, the valve is raised and the water entering through the inlet aperture 12^a, passes around the cylindrical valve body 20^a, through the apertures 23^a, therein, which in this case will have their combined areas substantially equal to or in excess of the area

of the aperture 12 so that all the water entering the valve casing may pass upwardly through the hollow valve body. The discharge aperture 15^a being closed by the cylindrical valve body when the latter is in raised position, the water will pass through outlet 17^a to a suitable tank and gradually accumulate in the same until the pressure therein equals the initial pressure of the incoming water, when further admission of water is prevented. Upon the seat being released the valve descends by means of the spring 27^a and is also assisted in closing by the pressure of water above the valve and the contents of the tank are rapidly discharged through the aperture 15^a to the rim flush, thus setting up the siphonic action, breaking the liquid seal, discharging the contents of the bowl, and cleansing the bowl, and reestablishing the liquid seal.

In both forms of my invention it will be seen that a light spring 27 (or 27^a) will be sufficient to close the small inlet aperture 12 (or 12^a) so that injurious strain upon the spud 45 which supports the valve casing and connects it to the bowl is avoided.

What I claim and desire to secure by Letters Patent is:—

1. In a water closet valve, the combination with a valve casing provided with a flushing aperture, and interior cylindrical guiding portions provided with an outlet aperture in the cylindrical wall thereof between the upper and lower ends of said guiding portions, said outlet aperture communicating with said flushing aperture, said casing having a tank supplying and relieving aperture communicating with the interior of the casing above said cylindrical guiding portions and being also provided with an inlet aperture at one end of the casing substantially in line with the axis of said guiding portions, portions of the casing adjacent to said inlet aperture being of greater internal diameter than the cylindrical guiding portions, of a hollow cylindrical valve body fitting said cylindrical guiding portions and adapted to close said outlet aperture when the valve is in open position, said valve body being open at the end remote from the inlet aperture and closed at the other end, the closed end of said valve body being provided with a valve for normally closing the inlet aperture in the casing, said valve body having lateral apertures in its walls communicating with the interior of the valve body, a spring for holding said valve body normally in position with its inlet valve closed, and means for moving the valve body against its spring to open the inlet aperture and simultaneously close the outlet aperture, whereby the water will pass around and through the valve body to the tank, and on the return movement of the valve body to

close the inlet aperture, the outlet aperture will be open to permit the tank to discharge through the flushing aperture.

2. In a water closet valve, the combination with a valve casing provided with a flushing aperture, interior cylindrical guiding portions, an outlet aperture between the upper and lower parts of said guiding portions connected with said flushing aperture, a tank supplying and relieving aperture connecting with the casing above said guiding portions, and an inlet aperture below said guiding apertures, portions of the casing below said guiding portions being of greater internal diameter, of a hollow cylindrical valve body engaging said guiding portions, and adapted to close said outlet aperture when in open position, said valve body being open at one end and closed at the other and provided at its closed end with a valve normally closing the inlet aperture, said valve body having apertures in its walls, a spring engaging said valve body and normally holding the inlet valve closed, said valve casing being provided with an auxiliary discharge aperture below said guiding portions, a connection therefrom to the jet of the bowl, and means for moving said valve body to open the inlet aperture and close said outlet aperture, whereby on the opening movement of the valve, water will be discharged up through the valve to the tank and portions of the water will be discharged to the jet to break the seal and create a continuous suction through the open trap for ventilating, and on closing the valve, the water in the tank will be discharged from the flushing aperture.
3. In a water closet valve, the combination with a valve casing provided with a flushing aperture, interior cylindrical guiding portions, an outlet aperture between the upper and lower parts of said guiding portions connected with said flushing aperture, a tank supplying and relieving aperture connecting with the casing above said guiding apertures, and an inlet aperture below said guiding apertures, portions of the casing below said guiding portions being of greater internal diameter, of a hollow cylindrical valve body engaging said guiding portions, and adapted to close said outlet aperture when in open position, said valve body being open at one end and closed at the other and provided at its closed end with a valve normally closing the inlet aperture, said valve body having apertures in its walls, a spring engaging said valve body and normally holding the inlet valve closed, said valve casing being provided with an auxiliary discharge aperture below the said guiding portion, one of said apertures being connected to the jet of the bowl and the other of said apertures being connected to the rim flush passage thereof, whereby upon opening the valve a

portion of the water will be delivered to the tank and portions will be discharged through the jet to break the seal of the trap and create a continuous suction through the open trap for ventilating, and a portion of the water will be discharged through the rim flush to wet the side walls of the bowl above the liquid level of the trap and on closing the valve the water will be discharged through the tank of the flush aperture.

4. In a water closet valve, the combination with a valve casing provided with a flushing aperture, interior cylindrical guiding portions, an outlet aperture between the upper and lower parts of said guiding portions connected with said flushing aperture, a tank supplying and relieving aperture connecting with the casing above said guiding apertures, and an inlet aperture below said guiding apertures, portions of the casing below said guiding portions being of greater internal diameter, of a hollow cylindrical valve body engaging said guiding portions, and adapted to close said outlet aperture when in open position, said valve body being open at one end and closed at the other and provided at its closed end with a valve normally closing the inlet aperture, said valve body having apertures in its walls, a spring engaging said valve body and normally holding the inlet valve closed, said valve casing being provided with an auxiliary discharge aperture below said guiding portions and a connection therefrom to the jet of the bowl, a pivoted closet seat and operative mechanism for connecting said valve with the seat for normally holding the seat in raised position, whereby on the depression of the seat the valve will be automatically discharged, delivered to the tank and to the jet to break the seal and continuously create suction through the open trap while the seat is depressed, and on releasing the seat the valve and seat are returned to normal position and the water accumulated in the tank is discharged through said flushing aperture.

5. In a water closet valve, the combination with a valve casing provided with a flushing aperture, interior cylindrical guiding portions, an outlet aperture between the upper and lower parts of said guiding portions connected with said flushing aperture, a tank supplying and relieving aperture connecting with the casing above said guiding apertures, and an inlet aperture below said guiding apertures, portions of the casing below said guiding portions being of greater internal diameter, of a hollow cylindrical valve body engaging said guiding portions, and adapted to close said outlet aperture when in open position, said valve body being open at one end and closed at the other and provided at its closed end with a valve normally closing the inlet aperture, said valve body having

apertures in its walls, a spring engaging said valve body and normally holding the inlet valve closed, said valve casing being provided with auxiliary discharge apertures, 5 one of which is connected with the jet of the bowl and the other with the rim flush passage independent of said flushing aperture, a pivoted closet seat, connections between said seat and said valve normally holding the seat 10 in lifted position, whereby on the depression of the seat the valve will be open to admit water to the tank and simultaneously and automatically discharge portions to the rim flush passage continuously and to the jet

passage breaking the liquid seal and continuously producing suction through the open trap while the seat is depressed for ventilating, and on releasing the seat the valve and seat are returned to normal position by the spring and water accumulated 15 in the tank is discharged from said flushing aperture.

In testimony whereof I affix my signature, in the presence of two witnesses.

PHILIP HAAS.
